RECREATIONAL WATER VEHICLE

Louis W. Schmitz, 518 19th Ave., Gilbertville, Iowa
50634, and Norman E. Hinkel, 3516 Rosehill Terrace,
Waterloo, Iowa 50701

Filed Mar. 14, 1972, Ser. No. 234,692

Term of patent 14 years

Int. Cl. D21—02

U.S. Cl. D12—62

FIG. 1.

FIG. 2.

FIG. 3.

FIG. 4.

FIG. 5.

FIG. 1 is a perspective view of a recreational water vehicle showing our new design;

FIG. 2 is a side view thereof, as seen looking straight ahead at FIG. 1;

FIG. 3 is a front view thereof, as seen looking from the left of FIG. 1;

FIG. 4 is a rear view thereof, as seen looking from the right of FIG. 1; and

FIG. 5 is a bottom view thereof, as seen looking upward at FIG. 1.

We claim:

The ornamental design for a recreational water vehicle, as shown and described.
